Fig. 2

To all whom it may concern:

Be it known, that we, Leo Ivan Bruce and Philip Frederick Huy, have invented a new, original, and ornamental Design for Clock, of which the following is a specification, reference being had to the accompanying drawing, forming a part hereof.

In the drawing, Fig. 1 is a front perspective view of a clock embodying our new design, while Fig. 2 is a side elevational view of the clock shown in Fig. 1. The op-

posite side of the clock is the same in appearance as that shown.

We claim:

The ornamental design for a clock, as shown and described.
